UNITED STATES PATENT OFFICE

HARVEY W. BALL, OF ALLIANCE, OHIO, ASSIGNOR TO THE MORGAN ENGINEERING COMPANY, OF ALLIANCE, OHIO, A CORPORATION

CRANE TROLLEY

Application filed December 19, 1931. Serial No. 582,113.

This invention relates to improvements in crane trolleys, and more particularly to a speed reducing device to be used inside the hoist drum of such a trolley in place of the usual large train of gearing.

One of the objects of the invention is to combine in a novel manner, a known type of reduction gearing with a crane drum.

Other objects of the invention are to do away with the usual costly and large gear train, allow the trolley to be so designed as to lower its height, and permit the trolley to approach closer to both sides and ends of building.

A further object is to provide a crane trolley which is smaller and lighter than those heretofore known and which can be readily lubricated.

A further object is to make possible much higher lifts in much less space for hoist than would be required for the usual trolley of equal lift and capacity.

Another object is to furnish a crane trolley in which the gears of the reducing mechanism is housed, thus eliminating the use of exposed gears.

With the foregoing objects outlined and with other objects in view which will appear as the description proceeds, the invention consists in the novel features hereinafter described in detail, illustrated in the accompanying drawings, and more particularly pointed out in the appended claims.

In the drawings, Fig. 1 is a top plan view of the improved trolley.

Fig. 2 is a transverse sectional view on the line 2—2 of Fig. 1.

Fig. 3 is a transverse sectional view of the crane drum taken on the line 3—3 of Fig. 4.

Fig. 4 is a longitudinal sectional view of the drum.

Referring to the drawings, 5 designates the frame of the improved crane trolley which has wheels 6 that run on the usual rails, not shown. Two of these wheels are mounted on an axle 7 which is driven by a motor 8 through a suitable train of gearing arranged in a housing 9.

In accordance with the present invention,

the crane drum 10 is of hollow formation and one of its ends 11 rotates upon a stationary shaft 12 which is keyed to a suitable support 13. A rotatable shaft 14 extends through a rotatable trunnion 15 at the other end of the drum, and the trunnion is mounted in a suitable bearing 16. The shaft 14 is driven by any suitable prime mover such as an electric motor 17. The shaft 14 is provided with oppositely extending eccentrics 18 and its left end 19 rotates in suitable anti-friction bearings 20 arranged in the hollow end 21 of the stationary shaft 12.

Each eccentric is surrounded by a pair of anti-friction bearings 22 on which there is a ring 23 that is pivotally connected as shown at 24, to the inner ends of radially movable plungers 25. These plungers slide in a plunger holder 26 which is fixed to the stationary shaft by means of bolts or the like 27. The outer ends of the plungers are pointed and they cooperate with a circular series of rack teeth 28 cut in a hollow cylinder 29 which preferably forms an integral part of the drum.

In operation, the shaft 14 in rotating, will cause its eccentrics 18 to push the plungers 25 radially outward in the plunger holder 26. As the plungers are pushed radially outward, their pointed ends engage on the angle slopes of the rack teeth 28, thereby forcing the drum 10 forward but rotating it at a slower speed than that of the shaft 14. The action of the plungers on the rack teeth may be likened to a tread mill, in that the plungers simply reciprocate radially, and their pointed ends act as feet to rotate the drum 10.

The advantages of this type of hoist are that it does away with the usual costly and large gear trains, and allows the trolley to be of less height in order that it may approach closer to both the runway and bridge rails. Furthermore, the trolley is smaller, lighter and can be readily lubricated, and at the same time, all exposed gears are avoided, this being an added safety feature.

From the foregoing it is believed that the construction, operation and advantages of the invention may be readily understood by those skilled in the art, and it is apparent

that changes may be made in the details disclosed without departing from the spirit of the invention, as expressed in the claims.

What is claimed and desired to be secured by Letters Patent is:

1. A crane trolley including a prime mover having a shaft, a rotatable crane drum, a stationary plunger holder, a ring within the plunger holder, means on the shaft for moving the ring in an eccentric path, plungers pivotally connected to the ring and slideable in said holder, and a circular rack having teeth engaged by the plungers during radial reciprocation of the latter for causing rotation of the drum.

2. A crane trolley including a prime mover having a shaft, a rotatable crane drum, a stationary plunger holder, a ring within the plunger holder, means on the shaft for moving the ring in an eccentric path, plungers pivotally connected to the ring and slideable in said holder, a circular rack having teeth engaged by the plungers during radial reciprocation of the latter for causing rotation of the drum, and a stationary shaft for the drum to which the plunger holder is rigidly connected.

3. A crane trolley including a prime mover having a shaft, a rotatable crane drum, a stationary plunger holder, a ring within the plunger holder, means on the shaft for moving the ring in an eccentric path, plungers pivotally connected to the ring and slideable in said holder, a circular rack having teeth engaged by the plungers during radial reciprocation of the latter for causing rotation of the drum, and a stationary shaft for the drum provided with a cavity, the prime mover shaft extending into said cavity and being partially supported by the stationary shaft.

4. In an apparatus of the character described, a driving shaft, a stationary shaft, a hoisting drum mounted on said shafts, the driving shaft having an eccentric arranged within the drum, a ring surrounding the eccentric and actuated by the eccentric, plungers pivotally connected to said ring, a stationary holder in which the plungers move radially, and a circular toothed rack arranged in the drum and engaged by the plungers for transmitting movement to the drum from the driving shaft.

5. In an apparatus of the class described, a stationary shaft, a driving shaft coaxial therewith, one end of one shaft extending into one end of the other shaft and being supported by the latter, an eccentric on the driving shaft, a ring actuated by the eccentric, a plunger holder fixed to the stationary shaft, radially movable plungers slideable in said holder and pivotally connected to said ring, said eccentric, ring and plunger holder being arranged within the drum, and a circular toothed rack in the drum actuated by said plungers.

6. In combination, a rotatable shaft, a rotatable crane drum, a stationary plunger holder positioned within the drum and having radially disposed bores, a ring within the plunger holder, means on the shaft for moving the ring in an eccentric path, plungers pivotally connected to the ring and slideable in the bores of the holder, and a circular rack fixed to the drum and having teeth engaged by the plungers during radial reciprocation of the latter for causing rotation of the drum.

7. In an apparatus of the character described, a stationary shaft having a bearing at one end thereof, a driving shaft having one of its ends mounted in said bearing, a hoisting drum mounted on said shafts, the driving shaft having an eccentric arranged within the drum, a ring surrounding the eccentric and actuated by the latter, plungers pivotally connected to said ring, a stationary holder having bores in which the plungers are movable radially, means rigidly uniting said holder with the stationary shaft, and a circular toothed rack arranged within and fixed to the drum and engaged by the plungers for transmitting movement from the driving shaft to the drum.

In testimony whereof, I have signed this specification.
